UNITED STATES PATENT OFFICE

ARTHUR E. COLLINS, OF CUYAHOGA FALLS, OHIO, ASSIGNOR, BY MESNE ASSIGNMENTS, TO THE MILLER RUBBER COMPANY, INC., OF WILMINGTON, DELAWARE, A CORPORATION OF DELAWARE

MEANS FOR PRESSING AND TRIMMING TAPE REINFORCED SEAMS OF SHEET RUBBER ARTICLES

Application filed December 20, 1929. Serial No. 415,543.

My said invention relates to improved means for trimming off the reinforcing tapes or ribbons of bath caps and similar articles and increasing the weld between the end portions of the ribbon and the underlying seam portions.

In an application Serial No. 415,545 filed by be in the United States Patent Office of even date herewith, I have disclosed means for applying a continuous tape or ribbon successively to the cut together seams of bath caps and for automatically severing the ribbon or tape between the successive caps.

In this operation, it is impracticable to sever the tape or ribbon flush with the edges of the cap, and the caps therefore issue from the machine with a portion of the tape issuing from each end of the seam of the cap in the shape of a tab which must be trimmed off flush with the edge of the cap to give a proper finish.

The present invention aims to provide apparatus by which such trimming may be accurately effected in an expeditious and economical manner.

The invention aims also to provide means for increasing the weld or adhesive union between the end portions of the reinforcing tape or ribbon and the underlying seamed portions of the cap.

With these and other objects in view, which will hereinafter appear, the invention includes the novel features of construction and arrangement and combination of parts hereinafter described, the said invention being defined by the claims appended hereto.

What I at present consider the preferred embodiment of the invention is illustrated in the accompanying drawings in which:

40 Figure 1 is a side view of the machine or apparatus.

Fig. 2 is a front view.

Fig. 3 is an enlarged detail showing the hammer in front elevation and lower portion 45 of head 7 in section and the anvil in cooperating position.

Fig. 4 is a section on line 4—4 of Fig. 3.

Fig. 5 is a plan view of the hammer.

Fig. 6 shows the knife in side and end elevation, and

Fig. 7 is a plan view of the anvil.

It will be understood that this machine functions as a step in the complete operation of making up bathing caps and like articles and that the caps are conducted to the operator of the machine herein described from the reinforcing machine of my said application by a conveyor belt, the operator removing the cap from the conveyor, subjecting it to the action of the machine herein described, and replacing it upon the same or another conveyor to be conducted thereby to the vulcanizing apparatus.

My present apparatus or machine includes an anvil or platen and a combined ribbon cutter and presser member or hammer co-operating therewith which are preferably mounted in or carried by apparatus of the ordinary punch press type, including a rocking head 1 mounted upon a table frame 3 and capable of being set in any desired angular position for convenience of the operator by the arcuate slot and bolt connection 2, which, being well known, requires no more specific description.

On the supporting plate 4 of the head 1 is fixed the anvil 5, so shaped and alined on the base plate as to permit the operator to easily place thereon the cap or other article in position to be operated on by the hammer 6 and cutter 15 as hereinafter more fully described mounted on or carried by the lower end of the reciprocating head 7.

This is forced down with a hammer like action at the required time (after the cap has been properly positioned), by the operator depressing a treadle lever 8 which is connected by a rod 8a to a clutch 9 which serves to connect drive pulley 9a with the eccentric shaft 11; pulley 9a may be driven by belt 10 from an overhead shaft (not shown) this being shown as merely a convenient means of applying power.

Eccentric shaft 11 imparts rectilinear reciprocating movement to the head 7 in the manner well understood by those familiar with the action of punch presses, and break means 11a of the known type are provided to check the movement of the shaft when the drive is disconnected.

A wire guard 12 is preferably provided about the hammer 6 and affixed to the press frame to guard the operator, and if desired, an electric lamp 13 may be provided to properly illuminate the work at the point of action.

The hammer 6 before referred to is of rectangular shape and is provided with an upstanding integral shank 6a designed to be secured in a recess 7a in the head 7, the upper face portions of the hammer abutting against the lower face of the head and receiving the thrust.

The lower portion of the hammer body 6 is cut away or rebated on each side to provide angular grooves to receive the bars 14 which have beveled outer faces and countersunk apertures to receive the holding machine screws 14a which are tapped in to the relatively narrow portion of the hammer formed by said angular grooves as shown in Fig. 3, which relatively narrow portion cooperates with the corresponding narrow portion of the anvil.

The knife 15 of tool steel is of approximately T shape as shown in Figure 6 and is slidably seated in a vertical slot or guideway 6b in the hammer body, being inserted in the guideway from below and held therein by the angle bars 14 which are applied after the knife is inserted.

The knife is positioned transversely of the hammer body and near the rear face or end thereof so as to have its cutting edge aligned with the edge of the cap when the latter is positioned upon the anvil as shown in Fig. 4, whereby it will pinch off the excess or projecting portion of the ribbon as the hammer descends.

Springs 16 are placed in suitable bores or recesses over the T head of the knife to normally press the same downwardly and cause its cutting edge to project below the knurled lower face 6c of the hammer which acts on the reinforced seam adjacent the edge of the cap, and these springs are retained in place by threaded plugs 16a tapped into the upper ends of the bores 16.

Proper clearance or space is provided in the guideway to permit the upward movement of the knife to cause its edge to recede on contact with the anvil, the downward movement of the knife within the guideway being limited by the bars 14 above described.

The anvil 5 is of T shape as viewed in plan having its wider portion towards the rear providing an upstanding vertically disposed relatively narrow portion 5a which is of substantially the width of the seam reinforcing band c of the cap or other article C, and providing also rear laterally projecting wings or shoulders 5y. When the cap is placed in position with its reinforced seam overlying the upper face of said narrow portion of the anvil, the portions of the cap on each side of the reenforced seam depend into approximately

the position indicated in Fig. 3 whereby the rear edges of each side of said seam abutting against the inner faces of the projections or shoulders 5y serve to accurately position the cap edge relative to the knife or cutter so that only the projecting tab will be cut and that exactly at the edge of the cap as will be clearly apparent from Fig. 4, the cutter being aligned with the inner faces of the shoulders.

The anvil is provided at its base with ledge portions which enable it to be secured to the plate 4 by machine screws 5a, and its upper face portion which cooperates with the hammer and cutter is preferably made in the shape of a renewable or replaceable wear plate of hardened or tool steel as indicated at 5b.

I have found it most advantageous to provide means for holding the tab or extension of the ribbon projected during the seam compressing and tab cutting operation and to this end I provide the anvil with communicating passageways 5c, 5d, 5e bored therein, the first mentioned being connected with pipe 17 leading to any suitable source of air under pressure (not shown) and the last mentioned discharging into the upper surface of the anvil beneath the cap seam and being inclined towards the rear. The resulting outwardly directed jet of air holds the tab extended and prevents any wrinkling of the cap seam portion, and facilitates the accurate cut off of the tab.

The amount of air discharged may be accurately regulated by the regulating screw 5f and the air pressure may be further regulated by valve 18 mounted in the pipe line directly below the table plate 4.

In practice, the operator picks the oncoming caps from the conveyor table, one at a time, and places them, with the seam and reinforcing ribbon opened out flat, upon the anvil, with the edge of the cap up against the T extensions thereof and the ribbon end floated out straight, due to the air jet playing thereagainst.

Now, by a slight pressure on the foot pedal 8, the hammer is dropped down to deliver its blow upon the seam and at the same instant, the knife 15 carried thereby, will perform its pinching off action on the ribbon end. Thereafter, the operator removes the article and replaces it upon an upper deck of the conveyor to be carried on to the inspectors.

It may be noted that there is a tendency of the pinched off ribbon end to still adhere to the cap edge, due to the tacky nature of the unvulcanized rubber, and this is a fault of advantage to the operator, as it usually carries the excess piece away with the cap to the vulcanizer, where in the curing operation, it will drop off easily and can be dispensed with thereafter without causing a gumming up at the punch press.

By providing a combination of trimmer

knife and hammer, I secure a neat accurately trimmed reinforcement and the weld between the end portion of the ribbon and cap is greatly strengthened by the compressing action of the hammer.

5 Counter mechanism may be attached to the ram 7 to facilitate the counting of the articles acted upon if desired.

Having thus described my invention what 10 I claim is:

1. Apparatus for the purpose described comprising an anvil having a relatively narrow seam supporting portion and lateral shoulders adjacent one end thereof, a presser member cooperating with said anvil, and 15 a cutter yieldably carried by said presser member and alined with the inner faces of said shoulders.

2. Apparatus for the purpose described 20 comprising an anvil having a relatively narrow seam supporting portion and lateral shoulders adjacent one end thereof, a presser member mounted for movement towards and from said anvil, said presser member having a transverse slot and rebated sides, a 25 knife seated in said slot having lateral shoulders, retaining bars secured in the said rebated sides and underlying the lateral shoulders of the knife, and spring means 30 carried by said presser member exerting pressure on said knife.

3. Apparatus for trimming a two piece 35 rubber article at the edge of one of the pieces, said apparatus comprising a stationary anvil member provided with stops for aligning the edge of one of the pieces with the line of trim, means carried by the anvil for pneumatically positioning the superfluous end 40 of the other piece across the line of trim, and a movable knife adapted to cooperate with the anvil to sever the superfluous end in alignment with the edge of the first named piece.

4. Apparatus as defined by claim 3 including article compacting means associated with 45 the knife for cooperation with the anvil.

In testimony whereof, I affix my signature.
ARTHUR E. COLLINS.
